MULTIPLE CONTROL APPARATUS

Howard A. Thompson, Edgewood, Pa., assignor
to The Union Switch & Signal Company,
Swissvale, Pa., a corporation of Pennsylvania

Application October 20, 1928, Serial No. 313,772

117 Claims. (Cl. 246—134)

My invention relates to multiple control apparatus and is particularly adapted for, though not limited to, the control of the railway track switches and signals in a railway switching or interlocking layout.

One feature of my invention is the provision of means for controlling each of various partly inter-inclusive groups of devices by only one manually operable means. Another feature of my invention is the provision of interlocking control without the use of mechanically interlocked levers.

I will describe one form of apparatus embodying my invention, and will then point out the novel features thereof in claims.

The accompanying drawings, Figs. 1 to 4, inclusive, are diagrammatic views showing the constituent parts of one form of apparatus embodying my invention.

Referring first to Fig. 1, a stretch of railway is shown comprising a portion of main double track road X and a portion of an auxiliary double track road Y adjacent the junction thereof with road X. The reference characters A, B, C, D, E and F designate, respectively, the points at which traffic enters or moves out of this stretch of railway.

The reference characters 1, 1a, 2 and 2a designate the rails of road X and the respective rails of road Y. These rails are divided by insulated joints 3 to form a plurality of track sections aa—bb, bb—cc, cc—dd, dd—ee, ff—gg, etc., section gg—hh of road X being combined with the adjoining section of road Y in one track circuit and these two sections being therefore referred to hereinafter collectively as section gg—ii. Section hh—mm of road X is similarly combined with the adjoining section of road Y in another track circuit and these two sections are therefore referred to hereinafter collectively as section kk—mm.

Each track section is supplied with current by a transformer 4, the secondary winding of which is connected, through a usual impedance device 5, across the rails adjacent one end of the section. The primary winding of each of the transformers 4 is continuously supplied with current from terminals x and o of a suitable source. The transformer for section aa—bb supplies current through a pole-changing circuit controller 6 which is operated by a signal G adjacent point aa.

Each track section is provided with a track relay designated by the reference character T, with a distinguishing suffix, and connected

across the rails adjacent the opposite end of the section from the respective transformer 4. Relay T1, for section aa—bb, is of the type having a track winding 7 and a local winding 8 so as to be responsive to the direction of current supplied to section aa—bb through pole-changer 6 of signal G.

The reference character H, with a suitable distinguishing suffix, designates a switch or a derail each having a normal and a reverse position and located in a track of road X or Y. A crossover, including switches H4 and H4a, permits the movement of traffic from one to the other of the tracks of road X. Switches H1 and H3 join the tracks of road Y with the tracks of road X. Derails H1a, H2 and H5 perform the well known function of protecting traffic in advance, by derailing any train which attempts to pass while the derail is in its derailing position.

With all switches in the normal position, there are only two routes for directing traffic through the stretch of railway shown, but other routes may be arranged by changing the position of one or more of the switches, a total of six routes being thus provided with the layout of tracks and switches as shown. The two normal routes include the stretches of track between points bb and dd and between points gg and mm, respectively. With switch H3 reversed and switch H4 normal, a third route is provided including the stretch of track between points ii and dd. A fourth route includes switch H1 reversed, switch H4a normal, and the stretch of track between points kk and nn. A fifth route includes switch H3 normal, switches H4 and H4a reversed, and the stretch of track between points bb and nn. A sixth route includes switches H3, H4 and H4a reversed, and the stretch of track between points ii and nn. Traffic can move in either direction, that is, from left to right or from right to left, by each of these routes.

The reference character S, with a suitable distinguishing suffix, designates a signal placed adjacent one end of each route and which as here shown is of the semaphore type. Each of the signals S1 and S3 comprises a main arm a1 or a3, respectively, and a call-on arm a2 or a4, respectively. Each main and call-on arm operates a circuit controller having a contact closed only while the respective arm is indicating "stop" as, for example, contacts 26 and 332 of arm a1 of signal S1.

Main arm a1 provides a "proceed" indication for traffic to move from west to east, that is,

from left to right, as shown in the drawings, by the route from *kk* to *nn*, while track relays *T8* and *T9* for sections *kk—mm* and *mm—nn*, respectively, are energized. By means of call-on arm *a2*, a "slow speed" indication can be provided for a move over this route while either relay *T8* or *T9* is de-energized. Main arm *a3* of signal *S3*, similarly to arm *a1*, provides a proceed indication for eastbound traffic to move from point *gg* to *nn* while relays *T6*, *T8* and *T9* are energized. By means of call-on arm *a4*, a slow speed indication can be given for a move over this route while one or more of relays *T6*, *T8* and *T9* are de-energized. Signal *S5* is provided with a main arm *a5*, an auxiliary arm *a6*, and a call-arm *a7*, main arm *a5* governing traffic moves from *dd* to *bb* and auxiliary arm *a6* governing moves from *dd* to *ii*. Call-on arm *a7* can be used to provide a slow speed indication for either of these two routes while a track relay for a track section within the corresponding route is de-energized. High signals *S1*, *S3* and *S5* govern moves in the normal direction of traffic and dwarf signals *S2*, *S4* and *S6* govern moves in the reverse direction.

Each of the dwarf signals *S2*, *S4* and *S6* is provided with a main arm only which governs traffic over each of the routes beginning at that signal; for example, signal *S6*, while all switches are normal, governs traffic over the route from point *nn* to point *gg*; while switch *H4a* is normal and switch *H1* is reversed, signal *S6* governs traffic from point *nn* to point *kk*; while switches *H4a* and *H4* are reversed and switch *H3* is normal, signal *S6* governs traffic from point *nn* to point *bb*; and while switches *H4a*, *H4* and *H3* are reversed, signal *S6* governs traffic from point *nn* to point *ii*.

The track sections included in each of the routes described are known as detector track sections, whereas, sections *kk—jj* and *dd—ee* in the rear of signals *S1* and *S5*, respectively, are known as approach track sections.

Each switch or derail *H* is operated by a motor designated by the reference character *M* with a distinguishing suffix. A circuit controller, designated by the reference character *b*, with a distinguishing suffix corresponding to that of the respective switch, is also operated in conjunction with the switch. Whereas, circuits are shown for operating switches *H4* and *H4a* and derail *H5* only, it is to be understood that circuits similar to those for switches *H4* and *H4a* are provided for operating switch *H1* and derail *H1a*, and that circuits similar to those for operating derail *H5* are provided for operating switch *H3* and derail *H2*.

Relays *h4* and *h5*, having two windings *40* and *41*, are known as switch indication relays, being so controlled by pole-changers operated by the respective switch circuit controllers *b4* and *b4a*, and *b5*, as to be energized in a normal direction when the respective switches or derail occupy a normal position, and as to be energized in a reverse direction when the respective switches or derail occupy a reverse position. Relays *h1*, *h2* and *h3* are similarly controlled by switch *H1* and derail *H1a*, derail *H2*, and switch *H3*, respectively.

Relays *N1* and *N2* are controlled by the circuit controller contacts operated by signal arms *a*, and are hence known as signal indication relays.

Switches and derails *H* and signals *S* are controlled by manually operable circuit controlling devices referred to hereinafter as route levers, and which are grouped together in a suitable

control station such as an interlocking tower. One such device is provided for each direction of traffic through each route and one similar such device, known as a call-on lever, is provided for each call-on arm. These levers may conveniently be mounted, as shown in Fig. 4, on an operating board on which is a track diagram, known as a track model, which shows the relative locations of the switches, derails, and signals, within the stretch of railway of Fig. 1. Each call-on lever is mounted on the operating board adjacent the symbol for the call-on signal which it governs. Each route lever is mounted on the operating board adjacent the symbol for the signal which governs in the respective direction over the respective route. The reference "call-on" is painted on the operating board adjacent each call-on lever. Each route lever is distinguished by a suitable designation as to the route which such route lever controls.

Lamps are provided in the track model to indicate the position of each switch or derail. As shown for switch *H1*, lamp *e1* is lighted continuously, lamp *e2* is lighted when switch *H1* is normal only, and lamp *e3* is lighted when switch *H1* is reversed only. Similar lamps for indicating the positions of other switches and derails are similarly controlled. A green or yellow lamp, adjacent each signal diagram on the track model, becomes lighted when a route relay controlled by the respective route lever is energized. A yellow lamp adjacent each call-on signal diagram is lighted while a call-on relay controlled by the respective call-on lever is energized.

Referring now to Fig. 2, the circuits directly controlled by each route lever are here shown. A contact operated by each route lever is designated by the reference character *K* with a suitable distinguishing suffix; for example, contact *KFA* is operated by the route lever which controls the movement of traffic from point *F* toward point *A*. Similarly, contact *KAF* is operated by the route lever which controls traffic in the opposite direction over the same route from point *A* toward point *F*.

The relays controlled by such route lever contacts are referred to herein as route relays. The route relays for moves toward the left are designated by the reference character *g* with distinguishing suffixes, and the route relays for moves toward the right are designated by the reference character *r* with corresponding suffixes. These relays are energized by transformers *179*, *184*, *187*, *196*, *199* and *206*, each of which is continuously supplied with current from terminals *x* and *o*.

Approach locking is provided for the routes governed by high signals *S1*, *S3* and *S5* only. This is accomplished by means of stick circuits for the respective route relays. The approach locking for each of these routes is released by the opening of the respective stick circuit by means of manually controlled time releasing devices *J1* or *J2*, or by means of a detector track circuit relay, in the respective route, being de-energized by a train. Contacts *215* and *226* of releases *J1* and *J2*, respectively, in the approach locking circuits are so constructed as to remain closed for a measured interval of time after the operation of the respective releasing device has been started, whereas, contacts *315J1* and *322J2* operated by release *J1*, and *292J2* operated by release *J2*, and which are included in the circuits shown in Fig. 1, are so constructed as to open as

soon as the operation of the respective releases J¹ or J² has begun.

The relays in Fig. 2, which are designated by the reference character P with a distinguishing suffix, are hereinafter referred to as neutral switch relays or as first switch control relays. One such relay is provided for the control of switch H³, one for each of the derails H² and H⁵, one for the control of switches H⁴ and H^{4a}, 10 and one for the control of switch H¹ in conjunction with that of derail H^{1a}.

Relays of a type comprising two windings 40 and 41, and designated by the reference character U with a distinguishing suffix, are known 15 hereinafter as first polarized signal relays. Current is supplied to winding 40 of each of these signal relays by a transformer f, which has terminals 283 and 285 and a center tap 284 on its secondary winding. Current of one polarity is 20 supplied, by this transformer, to each relay U when a respective route relay for governing an eastbound move is energized, and current of the opposite polarity is supplied to each relay U when a respective route relay for governing a west- 25 bound move is energized. The primary winding of transformer f is continuously supplied with current from terminals x and o.

Referring now to Fig. 3, the relays designated by the reference character m and having two 30 windings 40 and 41, are referred to hereinafter as polarized switch relays or as second switch control relays, one of these being provided for each of the first switch control relays P shown in Fig. 2. For each switch and derail and each 35 combination of switches or of a switch and a derail for which switch control relays are provided, there is a reverse indication relay designated by the reference character t and a normal indication relay designated by the reference character i, 40 each being provided with a distinguishing suffix, corresponding to that of an associated switch or derail. The relays designated by the reference character Q, and having two windings 40 and 41, are known as second polarized signal relays or 45 as auxiliary signal control relays, one of these being associated with each first polarized signal relay U. The circuits for controlling relays Q may be referred to as a route check circuit network since they are also controlled by switch indication relays i and t to check the positions of 50 the various switches of the routes. The circuits shown in Fig. 1 and which are controlled by relays Q for controlling the signals may be referred to as a signal control circuit network. The relays designated by the reference character n are referred to hereinafter as signal back locking relays, one of these being associated respectively with each of the signal indication relays N shown 55 in Fig. 1. The relays designated by the reference characters V and W are known as route locking relays, relays V being provided for eastbound moves and relays W being provided for west- 60 bound moves. The relays designated by the reference character R are known as call-on relays, 65 these being controlled by contacts operated by the call-on levers.

Included in the operating circuits of derail motor M⁵, are four asymmetric units d¹, d², d³ and d⁴. Similar asymmetric units, designated by the 70 reference letter d with distinguishing suffixes, are shown in the operating circuits of switch motors M⁴ and M^{4a}. Each of these units may be similar to those disclosed and claimed in Letters Patent of the United States, No. 1,640,335, granted to L. O. Grondahl, August 23, 1927.

The operating circuits for switch and derail motors M, including asymmetric units d, form no part of my invention, but were invented by Lester E. Spray. Such circuits are shown, described and claimed in a patent application, Serial No. 323,286 filed December 3, 1928 by said Lester E. Spray for Multiple control apparatus.

In each of the drawings, the contacts operated by the various relays or by the time releases J are identified by numbers, such numbers having suitable distinguishing exponents when such contacts are not shown adjacent the respective relay or release by which they are operated. The exponent for each of these contact numbers comprises the reference character and suffix of the 15 respective relay or release. For example, the exponent R¹, for contact 325^{R¹} shown in the control of arm a¹ of signal S¹ in Fig. 1, comprises the reference character R and its suffix 1 of relay R¹, shown in Fig. 3 and which operates contact 20 325^{R¹}. Similarly, exponent J¹ of contact 322^{J¹} shown in the control of arm a¹ of signal S¹ in Fig. 1, comprises reference character J and suffix 1 of time release J¹, shown in Fig. 2 and which operates contact 25 322^{J¹}.

Having thus described, in general, the arrangement and location of the various constituent parts of my invention, I will now proceed to explain the operation of the apparatus.

As shown in the drawings, all parts are in their 30 normal condition, that is, each track section is clear, each switch is in its normal position, each derail is in its normal or derailing position, each signal is indicating "stop", each lever on the operating board is in its normal position, and the 35 switch indicating lamps on the operating board are so lighted as to indicate that each switch and derail is normal.

Since all signals are at stop, relays N¹ and N², 40 controlled by circuit controllers operated by the signals, are energized. Current, for energizing relay N¹, flows from terminal x, through contact 22 of signal S⁶, wire 23, contact 24 of arm a⁴ of signal S³, contact 25 of arm a³ of signal S³, contact 26 of arm a¹ of signal S¹, contact 27 of arm a² of signal S¹, and winding of relay N¹ to terminal o. Current for relay N² flows from terminal x through contacts 16, 17 and 18 of arms a⁷, a⁶ and a⁵ respectively of signal S⁵, wire 19, 45 contact 20 of signal S⁴, contact 21 of signal S², and winding of relay N² to terminal o. 50

Since all switches and derails are in their normal position, polarized indication relays h are energized in the normal direction. Current for relay h⁵ flows from terminal x, through normally 55 closed contact 30a—30 of circuit controller b⁵, winding 40 of relay h⁵, and normal contact 31—31a of controller b⁵ to terminal o. Winding 41 of each relay h is continuously supplied with current from terminals x and o. The circuits 60 for winding 40 of relays h² and h³ are similar to that just described for h⁵ and are therefore not shown in the drawings. Winding 40 of relay h⁴ is energized by current flowing from terminal x, through normally closed contact 33 of 65 circuit controller b⁴, normally closed contact 34a—34 of circuit controller b^{4a}, winding 40 of relay h⁴, normally closed contact 35—35a of circuit controller b^{4a}, and normally closed contact 36 of circuit controller b⁴ to terminal o. 70 Relay h¹ is controlled by circuit controllers, operated in conjunction with switch H¹ and derail H^{1a}, in like manner as relay h⁴ is controlled, as just described, by circuit controllers b⁴ and b^{4a} 75

which are operated in conjunction with switches H4 and H4a.

Windings 41 of the second switch control relays m , shown in Fig. 3, are now energized by current flowing in their stick circuits in the normal direction through back contacts of the respective first switch control relays. Winding 48 of each relay m is continuously supplied with current from terminals x and o . The normal stick circuit for relay $m1$ passes from terminal x , through contact 83^{P1}, contact 84 of relay $m1$, winding 41 of relay $m1$, and contact 82^{P1} to terminal o . A normal stick circuit is also closed for each of the other second switch control relays $m2$, $m3$, $m4$ and $m5$ and, being similar to the circuit just described for relay $m1$, will be readily understood from the drawings.

All switches and derails being in their normal position, normal indication relays i are now energized. The circuit for relay $i5$ passes from terminal x , through normal contacts 65^{m5} and 65^{h5}, and winding of relay $i5$ to terminal o . Relays $i1$, $i2$, $i3$ and $i4$ are similarly controlled by normal contacts of the respective second switch control relays m and polarized switch indication relays h , and the circuits for relays $j1$, $j2$, $j3$ and $j4$ are therefore omitted from the drawings.

Since all route levers are in their normal position and all route relays g and r are therefore de-energized, first polarized signal relays $U1$ and $U2$ and, in turn, windings 41 of second polarized signal relays $Q1$ and $Q2$ are de-energized. Signal back locking relays $n1$ and $n2$ are therefore energized, the circuit for relay $n1$ passing from terminal x , through de-energized contact 143 of relay $Q1$, contact 144^{N1}, and winding of relay $n1$ to terminal o . Relay $n2$ is energized by a similar circuit passing from terminal x , through de-energized contact 145 of relay $Q2$, contact 146^{N2}, and winding of relay $n2$ to terminal o .

Route locking relays V and W are energized, both a pick-up and a stick circuit for each of these relays being closed. The pick-up circuit for relay $V1$ passes from terminal x , through contact 55^{T2}, contact 56^{T6} in multiple with contact 57^{t3}, and winding of relay $V1$ to terminal o . The stick circuit of relay $V1$ is completed through contact 58^{Q2}, which is closed while winding 41 of relay $Q2$ is either de-energized or is energized in its reverse direction, but which is open while relay $Q2$ is energized in the normal direction. The pick-up and stick circuits of relay $V2$ are similar to those just described for $V1$ and will be readily understood from the drawings. The pick-up circuit for relay $W1$ passes from terminal x , through contacts 42^{T9} and 44^{T8}, and winding of relay $W1$ to terminal o . A second pick-up circuit, now open, for relay $W1$ includes contact 43^{t4} in a branch path around contact 42^{T9} of the first pick-up circuit. The stick circuit for relay $W1$ is completed through contact 45^{Q1}, which is closed while winding 41 of relay $Q1$ is either de-energized or is energized in the normal direction, but which is open while relay $Q1$ is energized in the reverse direction. A second stick circuit, now open, for relay $W1$ includes contact 46^{t4} in a branch path around contact 45^{Q1} of the first stick circuit. The circuits for relay $W2$ are similar to those just described for relay $W1$ and will be readily understood from the drawings.

As shown in Fig. 4, lamp $e1$ for switch $H1$ is continuously supplied with current from terminals x and o . Lamp $e2$ is lighted by current flowing from terminal x , through contact 343¹¹, and

lamp $e2$ to terminal o . Similar lamps for the other switches and derails are lighted by exactly similar circuits controlled by contacts of the respective indication relays.

I will now assume that the towerman desires to permit a train approaching point E to proceed toward point D . He therefore reverses the lever on the operating board, adjacent the diagram of signal $S5$, which is distinguished by the designation "To D."

Contact KED in the circuit of relay $g5$, shown in Fig. 2, is thereby closed and relay $g5$ becomes energized by a circuit passing from the secondary winding of transformer 199 , through contacts 200^{g2}, 201^{r2}, 202^{s3}, 203^{r3}, 204^{s6}, 205^{r6}, contact KED, winding of relay $g5$, and contact 268 of relay $r5$ back to the secondary winding of transformer 199 . Relay $g5$, upon becoming energized, closes its front contacts 257^{s5} and 267 in the circuit of first switch control relay $P5$. Relay $P5$ thereupon becomes energized by current flowing from the secondary winding of transformer 199 , through the circuit of relay $g5$ as far as contact 205^{r6}, thence through the winding of relay $P5$, contact 257^{s5}, wire 286, and contact 267 of relay $g5$ back to the secondary winding of transformer 199 . Relay $P5$, upon becoming energized, opens its back contacts 138^{P5} and 139^{P5} in the normal stick circuit of relay $m5$ and then closes its front contacts 135^{P5}, 138^{P5} and 141^{P5} in the reverse pick-up and stick circuits of relay $m5$. Relay $m5$ now becomes energized, in the reverse direction, by current flowing in its reverse pick-up circuit from terminal x , through contacts 116^{T3}, 117^{V1}, 133ⁿ², 136^{t4}, 137^{t5}, front contact 138^{P5}, winding 41 of relay $m5$, and front contact 135^{P5} to terminal o . Relay $m5$, upon closing its reverse contact 142, completes its reverse stick circuit passing from terminal x , through contact 141^{P5}, contact 142, winding 41 of relay $m5$, and front contact 135^{P5} to terminal o .

Relay $m5$, upon becoming energized in reverse direction, closes its reverse contacts 333^{m5} and 338^{m5} in the reverse control circuit of motor $M5$ of derail $H5$. Current then flows from battery L , through reverse contact 333^{m5}, armature 334 of motor $M5$, asymmetric unit $d2$, field winding 335 of motor $M5$, contact 337 of circuit controller $b5$, asymmetric unit $d4$ and reverse contact 338^{m5} back to battery L . Motor $M5$ then operates derail $H5$ to its reverse or non-derailing position. Just at the completion of this operation of derail $H5$, contact 337 opens, thereby breaking the motor circuit.

During the movement of derail $H5$ from its normal to its reverse position, winding 48 of indication relay $h5$ is shunted through contacts 30c and 31c, and is therefore deenergized. Upon the completion of the operation of switch $H5$ to its reverse position, relay $h5$ becomes energized in the reverse direction by current flowing from terminal x , through contact 31b-31, winding 40 of relay $h5$, and contact 30-30b to terminal o . When relay $m5$ becomes energized in its reverse direction for an operation of derail $H5$, as just described, the circuit of normal indication relay $i5$ is opened at contact 65^{m5}. When relay $h5$ becomes energized in its reverse direction, the circuit for reverse indication relay $t5$ becomes closed and current flows from terminal x , through reverse contact 65^{m5}, contact 67^{h5}, and winding of relay $t5$ to terminal o . When relay $i5$ becomes deenergized, as just described, the circuit for lamp $e2$ for derail $H5$, on the operating board, becomes opened, thereby extinguishing this lamp $e2$. When reverse indication relay $t5$ becomes en-

5 energized, reverse lamp e_3 for derail H_5 , on the operating board, becomes lighted by current flowing through a front contact of relay t_5 which completes a circuit for lamp e_3 for derail H_5 , similar to that shown for lamp e_3 for switch H_1 . Relay t_5 , upon becoming energized, opens the pick-up circuit of relay m_5 , but relay m_5 continues energized by its stick circuit through front contacts 135^{P_5} and 141^{P_5} as long as relay P_5 continues energized.

10 Relay g_5 , upon becoming energized by the closing of contact **KED**, as previously described, closes its contact 247^{S_5} in the circuit of winding 41 of relay U_2 and also closes its contact 282^{S_5} in the circuit of winding 40 of relay U_2 . Relay U_2 thereupon becomes energized in its reverse direction. The circuit for winding 41 includes the circuit of relay g_5 from transformer 199 to contact 205^{P_6} , thence through winding 41 of relay U_2 , contact 20 247^{S_5} , wire 286 , and front contact 267 of relay g_5 back to the secondary winding of transformer 199 . The circuit for winding 40 of relay U_2 passes from terminal 285 of the secondary winding of transformer f , through contact 282^{S_5} , and winding 40 25 of relay U_2 to terminal 284 of transformer f .

With relay U_2 thus energized in its reverse direction, the reverse pick-up circuit of relay Q_2 , through reverse contacts 168^{U_2} and 172^{U_2} , becomes completed at contact 169^{t_5} when relay t_5 30 becomes energized upon the completion of the movement of derail H_5 to its reverse position. The reverse pick-up circuit of relay Q_2 passes from terminal x , through contact 169^{t_5} , contact 170^{t_3} , reverse contact 172^{U_2} , winding 41 of relay Q_2 , and reverse contact 168^{U_2} to terminal o . Relay Q_2 thereupon becomes energized in its reverse direction, opening the circuit of relay n_2 at contact 145 .

40 Relay Q_2 , upon becoming energized in the reverse direction, completes, at its reverse contact 291^{Q_2} , the operating circuit of arm a_5 of signal S_5 , and current then flows from terminal x , through contacts 287^{Q_2} , 288^{t_3} , 289^{t_5} , 290^{t_4} , reverse contact 291^{Q_2} , contact 292^{J_2} , back contact 293^{P_2} , contacts 294^{t_3} , 295^{t_2} , 296^{t_3} , and 297^{T_1} , and the operating mechanism of arm a_5 to terminal o . Arm a_5 is now operated to its 45° position, and, if relay T_1 is energized in its normal direction, arm a_5 will be further moved to its 90° position by current 50 passing from terminal x , through contact 28 of relay T_1 , wire 29 , and the 90° operating mechanism of arm a_5 to terminal o .

55 While relay g_5 is energized and relay T_1 is energized in its normal direction, a green lamp, designated by the letter G and mounted adjacent the diagram of arm a_5 of signal S_5 , is lighted by its circuit passing from terminal x , through contact 349^{S_5} , normal contact 350^{T_1} , and lamp G to terminal o . When relay T_1 is energized in its reverse direction while relay g_5 is energized, a yellow lamp, designated by the letter Y and mounted adjacent the diagram of arm a_5 of signal S_5 , is lighted by its circuit passing from terminal x through contact 349^{S_5} , reverse contact 350^{T_1} , and lamp Y to terminal o .

60 Arm a_5 , upon moving away from its stop position, opens its contact 18 in the circuit of relay N_2 which is thereby de-energized. Referring to the circuit for relay n_2 , it is clear that relay n_2 cannot again become energized until relay N_2 has become energized when arm a_5 has been returned to its stop position, and until winding 41 of relay Q_2 has become de-energized due to the de-energization of relay U_2 , which is in turn de-energized by the de-energization of g_5 when con-

tact **KED** of the respective route lever has been opened. Meanwhile, contact 133^{n_2} is open in the pick-up circuits of relay m_5 , thus insuring that relay m_5 cannot again be energized in its normal direction until relay g_5 has been de-energized by the return of its lever to the normal position, and until arm a_5 has been returned to the stop position. Upon the energization of relay Q_2 in its reverse direction for the clearing of arm a_5 , contact 51^{Q_2} in the stick circuit of route locking relay W_2 has been opened, thus breaking this stick circuit, but relay W_2 continues energized by its pick-up circuit.

10 I will now assume that with arm a_5 of signal S_5 indicating "proceed" a train approaches and de-energizes relay T_4 . The stick circuit of relay g_5 is thereby completed at contact 228^{T_4} , and passes from contact 285^{t_6} in the pick-up circuit of relay g_5 , through contact 226 of release J_2 , contacts 227^{T_3} and 228^{T_4} , contact 230 of relay g_5 , the winding of relay g_5 , and contact 268 of relay r_5 back to transformer 199 .

15 If, now, the towerman should desire to hold the train at signal S_5 , he will return to its normal position the lever which operates contact **KED**, thereby opening this contact. However, relay g_5 does not then become de-energized, since its stick circuit is closed, and arm a_5 of signal S_5 therefore continues to indicate "proceed" and derail H_5 cannot be returned to its derailing position. 20 The towerman can, however, de-energize relay g_5 by the operation of release J_2 which, at the beginning of its operation, opens its contact 292^{J_2} in the circuit of arm a_5 , thereby causing arm a_5 to be at once returned to its stop position, but which 25 does not open its contact 226 in the stick circuit of relay g_5 until after the lapse of a measured interval of time following the opening of contact 292^{J_2} . Hence, derail H_5 cannot be returned to its derailing position until a given interval of time 30 has passed after the return of arm a_5 to its stop position.

35 If, instead of attempting to hold the train at signal S_5 , the towerman has permitted the train to proceed by the route from E to D , the train 40 upon entering section cc — dd , de-energizes relay T_3 , thereby opening, at contact 227^{T_3} , the stick circuit of relay g_5 which will then become de-energized as soon as the towerman opens contact **KED**. The train, upon de-energizing relay T_3 , 45 also opens, at contact 294^{T_3} , the circuit of arm a_5 which then returns to the stop position. It will be noted that each of the relays T_3 , T_6 and T_8 is provided with a stick circuit and with a pick-up circuit which includes one or more route relay 50 back contacts. Since the pick-up circuit of relay T_3 includes contact 11^{t_5} , it is clear that relay T_3 , after being de-energized by a train, cannot again become energized until the towerman has opened lever contact **KED** and thus de-energized relay g_5 . 55 By means of this control of relay T_3 , stick control of arm a_5 of signal S_5 is provided. Stick control of arm a_1 of signal S_1 , of arm a_3 of signal S_3 , and of arm a_6 of signal S_5 is provided by contacts 15^{t_1} , 13^{t_4} and 10^{t_2} in the pick-up circuits of stick 60 track relays T_8 , T_6 and T_3 , respectively.

65 Relay Q_2 being energized in the reverse direction at the time the train de-energizes relay T_3 , route locking relay W_2 becomes de-energized due to the opening of contact 48^{T_3} while contact 51^{Q_2} 70 is open. Relay W_2 , upon becoming de-energized, opens its contact 102^{W_2} in the pick-up circuits of relay m_3 , thus preventing the possibility that the towerman may, by opening contact **KED** and closing contact **KEB** and thereby causing relay g_2 75

- and in turn relays P_1 and P_3 to become energized, reverse the direction of energization of relay m_1 and then of m_3 and thereby cause switch H_3 to be reversed after the train has passed signal S_5 .
- 5 While relay T_3 is de-energized by the train, derail H_5 cannot be returned to its derailing position since the pick-up circuits of relay m_5 are open at contact 116^{T_3} .
- I will further assume that while at least one 10 of the relays T_1 , T_2 and T_3 is de-energized, as by a train, causing arm a_5 of signal S_5 to indicate stop, the towerman finds it necessary to send another train into the route controlled by arm a_5 . He therefore reverses the call-on lever which 15 is mounted adjacent the diagram of signal S_5 on the operating board. Contact KE , operated by this call-on lever, is thereby closed and hence call-on relay R_2 , shown in Fig. 3, becomes energized by current flowing from terminal x , through 20 contact KE , and the winding of relay R_2 to terminal o . Relay R_2 , upon becoming energized, closes its front contact 293^{R_2} , completing the operating circuit of call-on arm a_7 , this operating circuit including the operating circuit of arm a_5 25 as far as contact 292^{J_2} , thence through front contact 293^{R_2} , contacts 299 and 300 operated by arms a_5 and a_6 respectively of signal S_5 , and the operating mechanism of arm a_7 to terminal o . Arm a_7 is then operated to its calling-on position.
- 30 Relay R_2 , upon becoming energized by its pick-up circuit as described, completes its stick circuit passing from terminal x , through contact 117^{R_2} , contact 118 of relay R_2 , and the winding of relay R_2 to terminal o . With this stick circuit completed, relay R_2 will now continue energized although the towerman returns the call-on lever to its normal position thus opening contact KE . Arm a_7 will therefore continue to display the calling-on indication until the towerman returns 35 the lever designated "To D" to its normal position, opening contact KED and thereby de-energizing relay g_5 . While relay R_2 is energized, a yellow lamp, designated by the letter Y and mounted adjacent calling-on arm a_7 on the operating board, is lighted by a circuit passing from terminal x , through contact 352^{R_2} , and lamp Y to terminal o .
- I will next assume that the towerman, after 40 the preceding train has passed out of the stretch of railway shown in Fig. 1, desires to permit a second train to move from point E toward point B . He therefore reverses the lever designated "To B' " and mounted adjacent the diagram of signal S_5 on the operating board, thereby closing contact KEB which completes the circuit of relay g_2 passing from the secondary winding of transformer 184 , through contacts 185^{g_3} , 186^{g_3} , 192^{g_4} , 193^{g_4} , 194^{g_5} , 195^{g_5} , 204^{g_6} , 205^{g_6} , and KEB , winding of relay g_2 , and back contact 262 of relay r_2 to the secondary winding of transformer 184 . Relay g_2 , upon becoming energized, closes its front contacts 255^{g_2} and 261 in the circuit of relay P_5 which then becomes energized by current flowing in the circuit of relay g_2 as far as 45 contact 205^{g_6} , thence through the winding of relay P_5 , contact 255^{g_2} , wire 286 , and front contact 261 of relay g_2 to the secondary winding of 184 . Winding 41 of relay m_5 then becomes energized in its reverse direction, causing the operation of 50 derail H_5 to its reverse position as previously described.

Relay g_2 , upon becoming energized, also closes its front contact 241^{g_2} as well as its front contact 261 in the circuit of relay P_3 . Relay P_3 then 55 becomes energized by a circuit which includes

the circuit of relay g_2 as far as contact 205^{g_6} , thence through the winding of relay P_3 , contact 241^{g_2} , wire 286 , and contact 261 to transformer 184 . Contact 109^{t_1} is, however, open in the reverse pick-up circuit of relay m_3 which, therefore, cannot be energized in its reverse direction until after switch H_1 has been reversed thus causing relay t_1 to become energized. However, relay g_2 upon becoming energized closes its contact 353^{g_2} as well as front contact 261 in the circuit of relay P_1 .

Relay P_1 then becomes energized by current flowing in the pick-up circuit of relay g_2 as far as contact 205^{g_6} , thence through the winding of relay P_1 , contact 353^{g_2} , wire 286 , and contact 261 to transformer 184 . Relay P_1 , upon becoming energized, completes the reverse pick-up circuit of relay m_1 which then becomes energized in its reverse direction by this circuit which is similar to that previously traced for relay m_5 and which can therefore be readily understood from the drawings.

Relay m_1 , upon becoming energized in its reverse direction, causes the operation of switch H_1 and derail H_1a , to their reverse positions similarly to the manner in which relay m_5 , upon becoming energized in its reverse direction, causes the operation of derail H_5 to its reverse position as previously described, the operating circuits for switch H_1 and derail H_1a being, however, in multiple as shown for switches H_4 and H_4a . Upon the completion of the operation of switch H_1 and derail H_1a to their reverse positions, relay h_1 becomes energized in its reverse direction by a circuit which is similar to the reverse control circuit which will hereinafter be traced for relay h_4 . Relay t_1 then becomes energized, closing its contact 109^{t_1} and thereby completing the reverse pick-up circuit of relay m_3 . Relay m_3 now causes the operation of switch H_3 to its reverse position, similarly to the manner in which relay m_5 causes the operation of derail H_5 to its reverse position as previously described.

Relay g_2 , upon becoming energized, causes the reverse energization of relay U_2 by its contacts 245^{g_2} and 281^{g_2} which are in multiple with contacts 247^{g_5} and 282^{g_5} , respectively, in the circuits previously described for relay U_2 . The circuit for winding 41 of relay U_2 , however, instead of including a portion of the pick-up circuit of relay g_5 as previously traced, now includes the portion of the pick-up circuit of relay g_2 from transformer 184 to contact 205^{g_6} , and, from wire 286 , passes through contact 261 of relay g_2 to transformer 184 . Relay g_2 , upon becoming energized, also closes its contact 351^{g_2} , thus causing a green lamp, designated by the letter G and mounted adjacent the symbol of arm a_6 of signal S_5 on the operating board, to become lighted by its circuit, shown in Fig. 4, passing from terminal x , through contact 351^{g_2} , and lamp G to terminal o .

After the energization of relays t_3 and t_5 , due to the operation of switch H_3 and derail H_5 to their reverse positions, and the subsequent reverse energization of relay Q_2 , the operating circuit for arm a_6 of signal S_5 becomes closed through contacts 298^{t_3} and 289^{t_5} as well as through reverse contact 291^{Q_2} , relay Q_2 having been energized in its reverse direction upon the closing of contacts 169^{t_5} and 171^{t_3} . Current now flows from terminal x , through contacts 287^{Q_2} , 288^{t_3} , 289^{t_5} , 290^{t_4} , reverse contact 291^{Q_2} , contact 292^{t_2} , back contact 293^{R_2} , contacts 294^{T_3} , 295^{T_2} and 298^{t_3} , and the operating mechanism of arm a_6 of signal S_5 becomes closed.

a6 to terminal *o*. Arm *a6* thereupon becomes operated to its proceed position.

Approach locking of the switches and derail in the route governed by arm *a6* is effected by means of a stick circuit for relay *g2* in a manner similar to that by which approach locking is accomplished by the stick circuit previously described for relay *g5*. The stick circuit of relay *g2* includes the pick-up circuit of relay *g2* as far as contact *205^{r6}*, thence through contact *226* of release *J2*, contacts *227^{T3}* and *228^{T4}*, contact *229* of relay *g2*, the winding of relay *g2*, and contact *262* of relay *r2* to transformer *184*.

The train, upon de-energizing relay *T3*, opens the stick circuit of relay *g2*, and the towerman can now de-energize relay *g2* by returning the lever designated "To B" to its normal position, thus opening contact *KEB*. Relay *g2*, upon becoming de-energized, opens, at its contacts *241^{r2}* and *255^{r2}*, the circuits of relays *P3* and *P5* respectively. Relay *P5*, upon becoming de-energized, completes the normal pick-up circuit of relay *m5* passing from terminal *x*, through contacts *116^{T3}*, *117^{V1}*, *133^{r2}* and *134^{r5}*, back contact *135^{P5}*, winding *41* of relay *m5*, and back contact *138^{P5}* to terminal *o*. Relay *m5*, upon becoming energized in its normal direction, completes, through its normal contact *140*, its own normal stick circuit.

Relay *m5*, upon becoming energized in its normal direction, also completes the normal operating circuit for motor *M5* of derail *H5*, this circuit passing from battery *L*, through normal contact *322^{m5}*, asymmetric unit *d1*, field winding *335* of motor *M5*, contact *336* of circuit controller *55*, asymmetric unit *d3*, armature *334* of motor *M5*, and normal contact *333^{m5}* back to battery *L*. With derail *H5* again in its normal position, relay *h5* becomes energized again in its normal direction and relay *i5* then again becomes energized as previously described.

By the de-energization of relay *P3*, switch *H3* is caused to return to its normal position similarly to the manner in which derail *H5* is caused to return to its normal position by the de-energization of relay *P5*.

I will now assume that, with all parts again in their normal condition, the towerman desires to permit a train, approaching point *B*, to move toward point *F*. He therefore reverses the lever which is adjacent the diagram of signal *S2* on the operating board and which is designated "To *F*". He thus closes contact *KBF*, completing the circuit of relay *r3* which passes from transformer *187*, through contacts *188^{r1}*, *189^{r1}*, *190^{r2}*, *191^{r2}*, *192^{r4}*, *193^{r4}*, *194^{r5}*, *195^{r5}*, *204^{r6}*, *205^{r6}* and *KBF*, winding of relay *r3*, and back contact *363* of relay *g3* to transformer *187*. Relay *r3*, upon becoming energized, causes the operation of switch *H3* to its reverse position in a manner similar to that already described as due to the energization of relay *g2*.

Relay *r3*, upon becoming energized, also closes the circuit of relay *P4*, which includes the pick-up circuit of relay *r3* as far as contact *205^{r6}*, thence through the winding of relay *P4*, contact *252^{r3}*, wire *286*, and front contact *264* of relay *r3* to transformer *187*. Relay *P4*, upon becoming energized, closes the reverse pick-up circuit of relay *m4* which then becomes energized in its reverse direction. Relay *m4*, upon becoming energized in its reverse direction, causes current to be supplied to the motors *M4* and *M4a* of switches *H4* and *H4a*, respectively, which then become operated to their reverse positions. Upon the

completion of the operation of switches *H4* and *H4a* to their reverse positions, switch indication relay *h4* becomes energized in its reverse direction by current flowing from terminal *x*, through contact *38* of circuit controller *b4*, contact *35b*—*35* of circuit controller *b4a*, winding *40* of relay *h4*, contact *34*—*34b* of circuit controller *b4a*, and contact *37*—*37a* of circuit controller *b4* to terminal *o*.

Relay *r3*, upon becoming energized, completes, at its contacts *249^{r3}* and *264*, the circuit of winding *41* of relay *U2*, and also closes the normal circuit for winding *40* of relay *U2*, this circuit passing from terminal *283* of transformer *f*, through contact *278^{r3}*, and winding *40* of relay *U2* to terminal *284* of transformer *f*. Relay *U2* then closes its contacts in the normal direction. Relays *t3* and *t4* being energized, and relay *Q2* being energized in its normal direction, the operating circuit of signal *S2* is now completed and passes from terminal *x*, through contact *306^{Q1}*, wire *304*, contact *303^{t4}*, wire *302*, contacts *308^{t3}* and *309^{Q2}*, and the operating mechanism of signal *S2* to terminal *o*. Signal *S2* is thereby cleared for a move over the route between points *ii* and *nn*.

Route locking of switches *H4* and *H4a* is accomplished by means of route locking relay *V1* which becomes de-energized when a train, upon passing signal *S2*, de-energizes relay *T6* which then opens contact *56^{T6}*.

From the foregoing descriptions of typical examples of operation, the controls for the remaining routes and directions of traffic will be readily understood by reference to the drawings.

From the examples of operation cited, it is clear that, in order to arrange any route and clear a signal for a given direction of traffic over such route, the towerman has only to reverse one route lever.

It is also clear that, when any route relay *g* or *r* is energized by the operation of the respective route lever to the reverse position, no other route relay can be energized for arranging a conflicting route or for causing a conflicting movement of any switch or derail within the route or for clearing the opposing signal for the route. My invention further provides that certain switches and derails cannot be operated to a given position until certain other switches and derails have been operated to a certain given position, and that no signal can be cleared until each switch and derail within the route governed by the signal is in the correct position.

As has been described, my invention provides approach and detector track circuit locking of switches and derails and also signal indication locking of switches and derails.

Although I have herein shown and described only one form of multiple control apparatus embodying my invention, it is understood that various changes and modifications may be made therein within the scope of the appended claims without departing from the spirit and scope of my invention.

Having thus described my invention, what I claim is:

1. In combination with a plurality of devices each of which is capable of responding in a given manner to current of one polarity and in a given different manner to current of the opposite polarity, a polarized relay for each of said devices, means for supplying each of said devices with said current of one polarity or the other according as the contacts of the respective said polar-

- ized relay are closed in their normal or their reverse direction, a neutral relay for each of said polarized relays, means for energizing each of said polarized relays in its normal or its reverse direction according as its neutral relay is energized or de-energized, a plurality of control relays, a manually operable contact for each of said control relays, means including the respective manually operable contact for energizing each of said control relays while certain others of said control relays are de-energized, and means for energizing each of said neutral relays while any one of a respective group of said control relays is energized.
- 15 2. In combination with a plurality of devices each of which is capable of responding in a given manner to current of one polarity and in a given different manner to current of the opposite polarity, a polarized relay for each of said devices, means for supplying each of said devices with said current of one polarity or the other according as the contacts of the respective said polarized relay are closed in their normal or their reverse direction, a plurality of control relays, a manually operable contact for each of said control relays, means including the respective manually operable contact for energizing each of said control relays while certain others of said control relays are de-energized, means for energizing each of said polarized relays with current of one polarity while any one of a respective group of said control relays is energized, and means for energizing each of said polarized relays with current of the opposite polarity while all relays in said respective group are de-energized.
- 30 3. In combination with a plurality of devices each of which is capable of responding in a given manner to current of one polarity and in a given different manner to current of the opposite polarity, a plurality of control relays, a manually operable contact for each of said control relays, means including the respective manually operable contact for energizing each of said control relays while certain others of said control relays are de-energized, means for supplying each of said devices with current of one polarity while any one of a respective group of said control relays is energized, and means for supplying each of said devices with current of the opposite polarity while all relays in said respective group are de-energized.
- 45 4. In combination with a plurality of devices each of which is responsive to electric current, a plurality of polarized relays each of which while energized in one direction permits current to be supplied to a respective group of said devices and while energized in the reverse direction permits current to be supplied to a second respective group of said devices, a plurality of control relays, a manually operable contact for each of said control relays, means including the respective manually operable contact for energizing each of said control relays while certain others of said control relays are de-energized, means for energizing each of said polarized relays by current of one polarity while any one of a first respective group of said control relays is energized, and means for energizing each of said polarized relays by current of opposite polarity while any one of a second respective group of said control relays is energized.
- 60 5. In combination with a plurality of devices each of which is capable of responding to a suitable form of energy and in a manner according to the manner of application of said energy

thereto, a plurality of control relays, a manually operable means for each of said control relays, means including the respective manually operable means for energizing each of said control relays while certain others of said control relays are de-energized, means for supplying each of said devices with energy applied in a given manner while any one of a respective group of said control relays is energized, and means for supplying each of said devices with energy applied in a given different manner while all control relays in said respective group are de-energized.

6. In combination, a stretch of railway track, a plurality of traffic governing devices for directing traffic over said stretch of track and each of which devices is capable of responding to a suitable form of energy and in a manner according to the manner of application of said energy thereto, a plurality of control relays, a manually operable device for each of said control relays, means including the respective manually operable device for energizing each of said control relays while certain others of said control relays are de-energized, means for supplying each of said governing devices with energy applied in a given manner while any one of a respective group of said control relays is energized, and means for supplying each of said governing devices with energy applied in a given different manner while all control relays in said respective group are de-energized.

7. In combination, a stretch of railway track, a plurality of track switches for directing traffic over said stretch of track, a plurality of signals for governing traffic over said stretch of track, a plurality of control relays, a manually operable device for each of said control relays, means including the respective manually operable device for energizing each of said control relays while certain others of said control relays are de-energized, means for operating each of said switches to one position while any one of a respective group of said control relays is energized, means for operating each of said switches to the opposite position while all the control relays of said respective group are de-energized, and means for clearing each of said signals while a respective said control relay is energized.

8. In combination, a stretch of railway track in which are included a plurality of track switches each having a normal and a reverse position, a plurality of routes by any one of which traffic can move in either direction through said stretch of track, a plurality of signals for governing traffic in either direction over said routes, a route relay for each traffic direction of each of said routes, a manually operable device for each of said route relays, means including the respective manually operable device for energizing each of said route relays while certain others of said route relays are de-energized, means for operating each of said switches to its reverse position when a route relay is energized for any route which includes said switch in such position, means for restoring each of said switches to its normal position upon the de-energization of all route relays which cause said switch to be operated to its reverse position, and means for clearing each of said signals when the route relay for the associated route and traffic direction is energized.

9. In combination, a stretch of railway track in which are included a plurality of track switches each having a normal and a reverse position, a plurality of routes by any one of which traffic can move in either direction through said

stretch of track, a plurality of signals for governing traffic in either direction over said routes, a route relay for each traffic direction of each of said routes, a manually operable device for each 5 of said route relays, means including the respective manually operable device for energizing each of said route relays while certain others of said route relays are de-energized, means for continuing the energization of each of several said 10 route relays independently of the respective manually operable device while a train is approaching the respective signal, means for operating each of said switches to its reverse position when a route relay is energized for any route which 15 includes said switch in such position, means for restoring each of said switches to its normal position upon the de-energization of all route relays which cause said switch to be operated to its reverse position, and means for clearing each 20 of said signals when the route relay for the associated route and traffic direction is energized.

10. In combination, a stretch of railway track in which are included a plurality of track switches each having a normal and a reverse 25 position, a plurality of routes by any one of which traffic can move in either direction through said stretch of track, a plurality of signals for governing traffic in either direction over said routes, a route relay for each traffic direction of each of 30 said routes, a manually operable device for each of said route relays, means including the respective manually operable device for energizing each of said route relays while certain others of said route relays are de-energized, means for continuing 35 the energization of each of several said route relays independently of the respective manually operable device while a train is approaching the respective signal, means for de-energizing each of said several route relays after a measured 40 interval of time when such route relay is being energized by an approaching train, means for operating each of said switches to its reverse position when a route relay is energized for any route which includes said switch in such position, means for restoring each of said switches 45 to its normal position upon the de-energization of all route relays which cause said switch to be operated to its reverse position, and means for clearing each of said signals when the route 50 relay for the associated route and traffic direction is energized.

11. In combination, a stretch of railway track in which are included a plurality of track switches each having a normal and a reverse position, a plurality 55 of routes by any one of which traffic can move in either direction through said stretch of track, a plurality of signals for governing traffic in either direction over said routes, a route relay for each traffic direction of each of said routes, a manually operable device for each of said route relays, means including the respective manually operable device for energizing each of said route relays while certain others of said route relays are de-energized, a control relay 60 for each of said switches, means for energizing each of said control relays while a said route relay is energized for any route which includes the respective said switch in its reverse position, means for operating each of said switches to its reverse position while the respective control relay is energized, means for restoring each of said switches to its normal position while the respective control relay is de-energized, and means 65 for clearing each of said signals when the route 70 relay for the associated route and traffic direction is energized.

relay for the associated route and traffic direction is energized.

12. In combination, a stretch of railway track in which are included a plurality of track switches each having a normal and a reverse position, a plurality 5 of routes by any one of which traffic can move in either direction through said stretch of track, a plurality of signals for governing traffic in either direction over said routes, a route relay for each traffic direction of each of said routes, a manually operable device for each of said route relays, means including the respective manually operable device for energizing each of said route relays while certain others of said route relays are de-energized, a control relay for 10 each of said switches, means for energizing each of said control relays while a said route relay is energized for any route which includes the respective said switch in its reverse position, a second control relay for each of said switches 15 and each of said second control relays having a normal and a reverse position, means for operating each of said second control relays to its reverse or its normal position according as the respective first control relay is energized or de-energized and when all said signals governing 20 over said switch are indicating "stop" and track conditions are satisfactory, means for operating each of said switches to its reverse or its normal position according as the respective second control relay is in its reverse or its normal position, and means for clearing each of said signals when the route relay for the associated route and traffic direction is energized.

13. In combination, a stretch of railway track 30 in which are included a plurality of track switches each having a normal and a reverse position, a plurality of routes by any one of which traffic can move in either direction through said stretch of track, a plurality of signals for governing 40 traffic in either direction over said routes, a route relay for each traffic direction of each of said routes, a manually operable device for each of said route relays, means including the respective manually operable device for energizing each of said route relays while certain others of said route relays are de-energized, means for operating each of said switches to its reverse position when a route relay is energized for any route which includes said switch in such position, means for restoring each of said switches 50 to its normal position upon the de-energization of all route relays which cause said switch to be operated to its reverse position, a plurality of signal control relays each having a normal and a reverse position, means for operating each of said signal control relays to its normal or its reverse position according as a route relay of a respective group for governing traffic in one direction is energized or a route relay of a respective group for governing traffic in the opposite direction is energized, an auxiliary signal control relay for each of said first signal control relays, each said auxiliary signal control relay having a normal and a reverse position, means for operating each said auxiliary signal control relay to its reverse or its normal position according as the respective said first signal control relay is in its reverse or its normal position and when all the switches of a respective route are properly arranged, and means for clearing each of said signals when the respective auxiliary signal control relay occupies the proper 60 normal or reverse position and when each of 70 75

the switches of the associated route is in the proper position.

14. In combination, a stretch of railway track in which are included a plurality of track switches, a plurality of routes by any one of which traffic can move in either direction through said stretch of track, a signal adjacent each end of each such route for governing traffic through said route in the one direction or the other respectively, an approach track circuit for each of several said signals each including a track relay, a detector track circuit for each route each including a track relay, a route relay for each traffic direction of each of said routes, a manually operable lever for each said route relay, means including the respective manually operable lever for energizing each of said route relays while the route relay for governing in the opposite direction over the same route and the route relays for all routes which conflict with said route are de-energized, means for continuing the energization of each of several said route relays independently of its control lever while the respective approach track relay is de-energized, a time releasing device for opening the control circuit of the signal associated respectively with each of said several route relays and for de-energizing each of said several route relays upon the subsequent lapse of a measured interval of time and while the associated lever is in a position for not energizing said route relay, a contact of the respective detector track circuit relay for the route controlled by each of said several route relays for de-energizing the respective route relay while the associated lever is in a position for not energizing said route relay, and means including said route relays for controlling said switches and said signals.

15. In combination, a stretch of railway track in which are included a plurality of track switches, a plurality of routes by any one of which traffic can move in either direction through said stretch of track, a signal adjacent each end of each such route for governing traffic through said route in the one direction or the other, respectively, a detector track circuit for each route each including a track relay, a route relay for each traffic direction of each of said routes, a manually operable lever for each said route relay, means including the respective manually operable lever for energizing each of said route relays, a first control relay for each of said switches, means for energizing each said first control relay through a front contact of either of the said route relays for any route which includes the respective switch in its reverse position, a second control relay for each of said switches responsive to the polarity of current flowing through its windings, a normal pick-up circuit for each said second control relay including a front contact of the track relay for the detector track circuit in which the respective switch is located as well as a back contact of the respective first control relay and a source of current, a reverse pick-up circuit for each said second control relay including a front contact of the track relay for the detector track circuit in which the respective switch is located as well as a front contact of the respective first control relay and a source of current, a normal stick circuit for each said second control relay controlled by a normal contact thereof and by a back contact of the respective first control relay, a reverse stick circuit for each said second control relay controlled by a reverse contact

thereof and by a front contact of the respective first control relay, means for operating each said switch to its reverse or its normal position according as its second control relay is energized in its reverse or its normal direction, and means including said route relays for controlling said signals.

16. In combination, a stretch of railway track in which are included a plurality of track switches, a plurality of routes by any one of which traffic can move in either direction through said stretch of track, a signal adjacent each end of each such route for governing traffic through said route in the one direction or the other respectively, a route relay for each traffic direction of each of said routes, a manually operable lever for each of said route relays, means including the respective manually operable lever for energizing each of said route relays, a polarized control relay for each of said switches, a reverse pick-up circuit for energizing each said polarized control relay in its reverse direction when a route relay is energized for any route which includes the respective switch in its reverse position, a normal pick-up circuit for energizing each of said polarized control relays in its normal direction when the route relays are de-energized for all routes which include the respective switch in its reverse position, means for operating each said switch to its reverse or its normal position according as the respective polarized control relay is energized in its reverse or its normal direction, a plurality of first polarized signal relays, means for energizing each of said first polarized signal relays in one direction when any one of a respective group of route relays for one direction of traffic is energized, means for energizing each of said first polarized signal relays in the opposite direction when any one of a respective group of route relays for the opposite direction of traffic is energized, a second polarized signal relay for each of said first polarized signal relays and each of which controls a respective group of several said signals, a polarized indication relay for each of said switches, means for energizing each of said polarized indication relays in its normal or its reverse direction according as the respective switch is in its normal or its reverse position, a normal and a reverse indication relay for each of said polarized indication relays, an energizing circuit for each of said normal indication relays controlled by a normal contact of the respective polarized indication relay and by a normal contact of the respective polarized control relay, an energizing circuit for each of said reverse indication relays controlled by a reverse contact of the respective polarized indication relay and by a reverse contact of the respective polarized control relay, a normal and a reverse circuit for energizing each of said second polarized signal relays in its normal or its reverse direction according as the respective said first polarized signal relay is energized in its normal or its reverse direction while all the switches in a respective route are in the proper position and while the opposing signal for said respective route is indicating "stop", a signal indicating relay for each of said second polarized signal relays and which is controlled by a contact operated by each signal which is controlled by the respective second polarized signal relay, a back locking relay for each of said signal indicating relays and which is controlled by a front contact of the respective signal indicating relay and by a contact closed while the

respective second polarized signal relay is de-energized, a route locking relay for each of several said switches which are not located in the first track circuit in advance of a signal which governs traffic over said switch, a pick-up circuit for each of said route locking relays controlled by a front contact of the track relay of each track circuit between the respective switch and a signal which controls traffic over said switch, a stick circuit for each of said route locking relays controlled by a contact closed while the second polarized signal relay for said signal which controls traffic over said switch is either de-energized or is energized in one direction but which contact is open while said second polarized signal relay is energized in the opposite direction for clearing said signal, a front contact of each of said route locking relays included in the pick-up circuits of the respective polarized control relays, a front contact of each back locking relay included in the pick-up circuits of each polarized control relay for switches over which traffic is governed by the signals which control the respective back locking relay, a main arm for each of said signals, a call-on arm for each of several said signals, a call-on relay for each call-on arm of said signals, a pick-up circuit for each of said call-on relays controlled by a manually operable device, a stick circuit for each of said call-on relays controlled by a front contact of each of said route relays which control the route of the main arm of the corresponding signal, means for controlling each main arm of said signals by the respective energized contact of its second polarized signal relay and by a front contact of the respective normal or reverse indication relay for each switch over which said signal governs, and means for controlling each call-on arm of said signals by a front contact of its call-on relay.

17. In combination, a stretch of railway track in which are included a plurality of track switches, a plurality of routes by any one of which traffic can move in either direction through said stretch of track, a signal adjacent each end of each such route for governing traffic through said route in the one direction or the other respectively, a manually operable traffic device for each traffic direction of each of said routes, a main arm for each of said signals, a call-on arm for each of several said signals, a manually operable call-on device for each of said call-on arms, means for controlling said main arms and said switches by said traffic devices, means for controlling said call-on arms by said call-on devices, a control board for said switches and signals on said control board a diagram showing the arrangement of said stretch of track and of said switches and said signals and also on said control board said traffic devices and said call-on devices mounted adjacent the diagrams of said signals which are controlled by the respective said traffic devices and said call-on devices, also on said control board a normal and a reverse lamp for each of said switches and each of which is lighted when the respective switch occupies its normal or its reverse position respectively.

18. In combination, a plurality of devices each of which is responsive to a suitable form of energy and in a manner according to the manner of application of said energy thereto, a manually operable means for each of given partly inter-inclusive groups of said devices, means for applying said energy in a given manner to all the said devices in each of said given partly inter-inclusive

groups when the respective said manually operable means is operated to a given position, and means for applying said energy in a given different manner to all the said devices in each of said partly inter-inclusive groups when said respective manually operable means is operated to a given different position. 5

19. In combination, a polarized switch relay for controlling operations of a railway track switch to one position or another according as said relay is energized in a normal or a reverse direction, a neutral switch relay, a normal pick-up circuit for said polarized relay controlled by a back contact of said neutral relay, a normal stick circuit for said polarized relay including one of its own contacts and controlled by a back contact of said neutral relay, and a reverse control circuit for said polarized relay controlled by a front contact of said neutral relay. 10

20. In combination, a polarized switch relay for controlling operations of a railway track switch to one position or another according as said relay is energized in a normal or a reverse direction, a neutral switch relay, a normal pick-up circuit for said polarized relay, a normal stick circuit for said polarized relay controlled by a back contact of said neutral relay, and a reverse control circuit for said polarized relay controlled by a front contact of said neutral relay. 15 25

21. In combination, a railway track switch, a polarized switch relay for controlling operations of said switch to one position or another according as said relay is energized in a normal or a reverse direction, a polarized indication relay energized in a normal or a reverse direction according as 30 said switch is in said first or said second position respectively, a normal indication relay controlled only by a normal polar contact of said switch relay and by a normal polar contact of said polarized indication relay, a reverse indication relay controlled only by a reverse polar contact of said switch relay and by a reverse polar contact of said polarized indication relay, and means controlled by said normal and reverse indication relays for controlling said switch. 35 40 45

22. In combination, a railway track switch, a polarized switch relay for controlling operations of said switch to one position or another according as said relay is energized in a normal or a reverse direction, a polarized indication relay energized in a normal or a reverse direction according as said switch is in said first or said second position, a normal indication relay controlled by a normal polar contact of said switch relay and by a normal polar contact of said polarized indication relay, a reverse indication relay controlled by a reverse polar contact of said switch relay and by a reverse polar contact of said polarized indication relay, and means controlled by said normal and reverse indication relays for controlling said switch relay. 50 55 60

23. In combination, a railway track switch controlled from a point remote from the switch, a polarized switch relay governed from said remote point for controlling operations of said switch to one position or another according as said relay is energized in a normal or a reverse direction, a polarized indication relay energized in a normal or a reverse direction according as said switch is in said first or said second position, a normal indication relay controlled by a normal polar contact of said switch relay and by a normal polar contact of said polarized indication relay, a reverse indication relay controlled by a reverse polar contact of said switch relay and by a reverse polar contact of said polarized indication relay. 65 70 75

verse polar contact of said polarized indication relay, and indication means at said remote point controlled by said normal and reverse indication relays.

5 24. In combination, a stretch of railway track including a plurality of traffic governing devices distributed among a plurality of routes, a diagram of said stretch, a plurality of control devices one for each of said routes arranged at the 10 representations of the corresponding entrance ends of said routes in said diagram, and means controlled by each of said control devices for operating a plurality of the traffic governing devices of the associated route.

15 25. In combination, a plurality of partly inter-inclusive groups of operable devices, a diagram showing the relative locations of said groups, a plurality of control instruments one for each of said groups arranged at the representations of the 20 corresponding groups in said diagram, and means controlled by each of said instruments for operating a plurality of the devices of the associated group.

25 26. Railway control apparatus comprising a control board, a plurality of track switches and signals for a plurality of routes, a diagram on said board showing the relative locations of said switches and signals as well as said routes, a plurality of devices mounted on said board one 30 for each of said routes at one end of the representation of the corresponding route, and means controlled by each of said devices for causing certain switches of its route to be operated and for causing a signal for its route to be cleared.

35 27. Railway control apparatus comprising a control board, a plurality of track switches which can be arranged to form a plurality of partly inter-inclusive routes over a given stretch of track, a diagram on said board showing the arrangement of said routes, a plurality of devices mounted on said board one for each of said routes at one end of the representation of the corresponding route, and means controlled by each of said devices for causing operation of all the 40 switches which are included in its route in a reverse position.

45 28. In combination, a plurality of railway track switches which can be arranged to form a plurality of routes over a given stretch of track, a signal for governing traffic movements over each of said routes, a control device for each of said routes, and means controlled by each of said control devices and interlocked non-mechanically for operating certain switches of its route and 50 for clearing the signal for its route.

55 29. In combination, a stretch of railway track including a plurality of switches, a signal for governing traffic movements over said stretch, a control device, and means controlled by said device 60 and interlocked non-mechanically for operating certain said switches and for clearing said signal.

65 30. In combination, a plurality of railway track switches which can be arranged to form a plurality of partly inter-inclusive routes over a given stretch of track, a control device for each of said routes, and means controlled by each of said control devices and interlocked non-mechanically with means controlled by certain other said control devices for operating all the switches which 70 are included in its route in a reverse position.

75 31. In combination, a stretch of railway track, a route including a plurality of track switches for directing traffic through said stretch, a stick relay, a manually operable device, a second manually operable device, a pick-up circuit for said

stick relay controlled by said first device, a stick circuit for said stick relay controlled by said second device, and means controlled by said stick relay for controlling said switches.

5 32. In combination, a stretch of railway track, a route including a plurality of track switches for directing traffic through said stretch, a stick relay, a manually operable device, a pick-up circuit for said stick relay controlled by said manually operable device, a stick circuit for said stick relay controlled by traffic conditions, and means controlled by said stick relay for controlling said switches. 10

15 33. In combination, a first, a second, and a third railway track switch, a first, and a second manually operable device, means controlled by said first device for operating said first switch, means controlled by said second device for operating said second switch, means controlled by said first device for operating said third switch, 20 and means controlled by said second device interlocked non-mechanically with means controlled by said first device for operating said third switch.

25 34. In combination, a railway track switch, a second railway track switch, a signal for governing traffic movements over said switches, a manually operable device, a second manually operable device, means controlled by said first device for operating said first switch, means controlled by said second device for operating said second switch, and means controlled by said first and second devices and interlocked non-mechanically with said switch operating means for clearing said signal.

35 35. In combination, a railway track switch, a second railway track switch, a signal for governing traffic movements over said switches, a manually operable device, a second manually operable device, means controlled by said first device for operating said first switch, means controlled by said second device for operating said second switch, and means controlled by said first switch and by said second device and interlocked non-mechanically with said switch operating means for clearing said signal. 40

45 36. In combination, a plurality of railway track switches, a manually operable device, a second manually operable device operated independently of said first device, means controlled by said first device for operating each of said switches to a given position and means controlled by said second device interlocked non-mechanically with means controlled by said first device for operating each of said switches to a given position. 50

55 37. In combination, a railway track switch, a second railway track switch, a manually operable device, a second manually operable device interlocked non-mechanically with said first device, means controlled by said first and second devices for operating each of said switches to a given position, and means controlled by said first and second devices for operating each of said switches to a second position. 60

65 38. A relay interlocking system, comprising a plurality of partly inter-inclusive groups of control relays, and means including back contacts of all the relays of each of said groups for controlling a corresponding relay of another of said groups.

70 39. A relay interlocking system, comprising a plurality of partly inter-inclusive groups of control relays, and means controlled by all the relays of each of said groups for controlling a corresponding relay of another of said groups.

75 40. A relay interlocking system, comprising a

plurality of control instruments, a plurality of partly inter-inclusive groups of control relays, and means controlled by each of said groups and by one of said instruments for controlling a corresponding relay of another of said groups.

41. A relay interlocking system, comprising a plurality of manually controllable instruments, a plurality of partly inter-inclusive groups of control relays, and means controlled by back contacts of the relays of each of said groups and by one of said instruments for controlling a corresponding relay of another of said groups.

42. A relay interlocking system, comprising a plurality of manually controllable instruments, a plurality of partly inter-inclusive groups of control relays, and means controlled by each of said groups and by one of said instruments for controlling a corresponding relay of another of said groups.

43. In combination, a stretch of railway track including a plurality of traffic governing devices distributed among a plurality of routes, a plurality of control devices one for each of said routes, and means controlled by each of said control devices and interlocked non-mechanically with means controlled by certain other said control devices for operating a plurality of the traffic governing devices as necessary for the associated route.

44. In combination, a plurality of partly inter-inclusive groups of operable devices, a plurality of control instruments one for each of said groups, and means controlled by each of said instruments and interlocked non-mechanically with means controlled by certain other said instruments for operating a plurality of the devices as necessary for the associated group.

45. In combination, a railway track switch, a first manually operable contact, a second manually operable contact mechanically independent of said first contact, a first relay controlled by said first contact for controlling said switch to a given position and a second relay controlled by said second contact and electrically interlocked with said first relay for controlling said switch to the same position as said first relay.

46. In combination, a stretch of railway track including a plurality of traffic governing devices distributed among a plurality of partly inter-inclusive routes, a plurality of independently operable manual control instruments, and means controlled in response to a single operation of each of said instruments for arranging the traffic governing devices as necessary for a corresponding one of said routes.

47. In combination, a stretch of railway track including a plurality of switches and signals for governing traffic movements over a plurality of partly inter-inclusive routes, a plurality of independently operable manual control instruments, and means controlled by each of said instruments for arranging the switches as necessary for a corresponding route and for clearing the signal for the same route.

48. In combination, a stretch of railway track including a plurality of switches and signals for governing traffic movements over a plurality of partly inter-inclusive routes, a plurality of independently operable manual control contacts, and a plurality of interlocked instruments controlled by said contacts for arranging the switches and clearing the signals for said routes.

49. In combination, a railway track switch, an approach track section, a signal for governing traffic movements over said switch from said ap-

proach section, a normally deenergized approach locking relay, manual means for controlling said signal, means controlled by said signal controlling means for energizing said relay, means controlled by a train in said approach section for retaining said relay in its energized condition, means for operating said switch between normal and reverse positions, and means controlled by said relay for at times preventing an operation of said switch.

50. In combination, a railway track switch, a signal for governing traffic movements over said switch, a normally deenergized approach locking relay, a manually operable device, means including said device for energizing said relay, a normally energized track relay which becomes deenergized if a train approaches said switch, a stick circuit including a back contact of said track relay for retaining said approach locking relay in its energized condition, means for clearing said signal only after said approach locking relay has become energized, and means for subsequently operating said switch only after said approach locking relay has become deenergized.

51. In combination, a railway track switch, an approach locking relay, a manually operable device, means including said device for energizing said relay, a normally energized track relay which becomes deenergized if a train approaches said switch, a stick circuit including a back contact of said track relay for retaining said approach locking relay in its energized condition, means for operating said switch to a given position only after said approach locking relay has become energized, and means for subsequently operating said switch to a second position only after said approach locking relay has been deenergized.

52. In combination, a stretch of railway track, a signal for governing traffic movements from a given direction over said stretch, a second signal for governing traffic movements from a second direction over said stretch, an approach locking relay, a manually operable device, means including said device and a train approaching said first signal for controlling said relay, means for clearing said first signal only after said relay has been energized, and means for clearing said second signal only when said relay is deenergized.

53. In combination, a section of railway track, a traffic governing device associated with said section, an approach section, a manually operable device, an approach locking relay, means including said device for energizing said relay, means controlled by a train in said approach section for retaining said relay in the energized condition, means controlled by a train in said first section for deenergizing said relay, and means controlled by said relay for controlling said traffic governing device.

54. In combination, a stretch of railway track containing a switch, a manually operable device, a stick relay, an approach track section for said switch, a pick-up circuit for said relay including said manually operable device, a stick circuit for said relay energizable only when said approach section is occupied and said first section is unoccupied, and means controlled by said relay for controlling said switch.

55. In combination, a railway track switch, an indication relay controlled in accordance with the position of said switch, and means controlled by said indication relay according to traffic conditions for controlling said switch.

56. In combination, a railway track switch, an

indication relay controlled by said switch, a signal for governing traffic movements over said switch, and means controlled by said indication relay according to the condition of said signal for controlling said switch.

57. In combination, a railway track switch, an indication means controlled by said switch, a signal for governing traffic movements over said switch, and means controlled by said signal according to the condition of said indication means for controlling said switch.

58. In combination, a railway track switch, an indication means controlled in accordance with the position of said switch, and means controlled by traffic conditions according to the condition of said indication means for controlling said switch.

59. In combination, a stretch of railway track, a main signal and a call-on signal for governing the movement of traffic through said stretch, a control relay, a signal circuit for clearing said main signal including a front contact of said control relay and a contact controlled in accordance with traffic conditions in said stretch, a signal circuit for clearing said call-on signal including a front contact of said control relay, means including a signal lever at a remote point for energizing said control relay, and manually operable means associated with said lever for effecting the closing of the circuit for said call-on signal in the event that said main signal fails to clear when said control relay is energized.

60. In combination, a stretch of railway track, a main signal and a call-on signal for governing the movement of traffic through said stretch, a signal relay, circuits controlled by said relay for clearing said main signal and for clearing said call-on signal, selecting means included in said circuits and arranged to permit the clearing of said main signal provided only said stretch is unoccupied and to prevent the clearing of said call-on signal when said main signal is cleared, and manually operable means for controlling said selecting means to clear said call-on signal, whereby a signal may be cleared for said stretch even though the stretch is occupied.

61. In combination, a section of railway track having a track relay, a main signal and a call-on signal for governing the movement of traffic through said section, a signal relay, a circuit for clearing the main signal closed only when the signal relay and the track relay are energized, a circuit for the signal relay including a manually controllable contact, a second relay, a circuit for clearing the call-on signal closed only when the signal relay and the second relay are energized, manually operable means for energizing the second relay, and means for preventing the clearing of the call-on signal except when the main signal is in its most restrictive condition.

62. In combination, a railway signal, a signal relay for controlling said signal, a control circuit for said relay, a call-on relay for controlling said signal, a manually controlled pickup circuit for said call-on relay, and a stick circuit for said call-on relay including a front contact of said signal relay.

63. In combination, a plurality of partly inter-inclusive traffic routes each including a plurality of railway switches, a signal to govern traffic over each route, a remote controlled switch controlling relay for each switch of each route to govern the operation of the switch, a remote controlled signal controlling relay to govern the operation of each signal, and circuit means to render each

remote controlled signal controlling relay ineffective to clear a corresponding signal unless each switch of the route over which traffic is governed by that signal agrees as to position with its remote controlled switch controlling relay.

64. In combination, a plurality of partly inter-inclusive traffic routes each including a plurality of railway switches, a signal to govern traffic over each route, a remote controlled switch controlling means for each switch to govern the operation of the switch, a remote controlled signal controlling relay to govern the operation of each signal, and a check locking circuit for each route controlled by the switch controlling means of each switch of the route and arranged to render the remote controlled signal controlling relay for the signal which governs traffic over the route ineffective to clear that signal unless each switch of the route agrees as to position with its respective remote controlled switch controlling means.

65. In combination, a railway switch having a normal and reverse position, a circuit controlling device controlled by said switch adapted to occupy one given position when the switch is normal and to occupy a second given position when the switch is reversed, a remote controlled switch controlling means having a normal and reverse position to establish the normal and reverse positions of said switch respectively, a circuit controlled by said circuit controlling device and said switch controlling means arranged to be closed only when said circuit controlling device and said switch controlling means both occupy their normal position or when both occupy their reverse position, a repeater relay controlled by said circuit and energized only when said circuit is closed, and a signal circuit to govern traffic over the switch closed only when said repeater relay is energized.

66. In combination, a plurality of intersecting railway tracks, trackway devices each having a normal and a reverse position capable of different combinations as to their normal and reverse positions to arrange said trackway into different routes, a signal for each route, remote controlled means having a normal and a reverse position for each trackway device to establish the corresponding position of its trackway device, a remote controlled relay for each signal to govern the operation of the signal, a circuit controlling means for each trackway device adapted to assume a normal or a reverse position in response to the normal or reverse position of the trackway device, a check locking circuit for each route controlled by the remote controlled means and the circuit controlling means of each trackway device of the route arranged to be closed only when there is agreement as to position between the remote controlled means and the circuit controlling means of each trackway device of the route, and means controlled by each check locking circuit to render the remote controlled relay ineffective to clear the signal for the route unless said circuit is closed.

67. In combination, a traffic route including a plurality of railway switches, a signal to govern traffic over the route, a remote controlled switch controlling relay for each switch of the route to govern the operation of the switch, a remote controlled signal controlling relay to govern the operation of the signal, and circuit means to render the remote controlled signal controlling relay ineffective to clear the signal unless each switch of the route agrees as to position with its remote controlled switch controlling relay.

68. In combination, a traffic route including a plurality of railway switches, a signal to govern traffic over the route, a remote controlled switch controlling means for each switch to govern the 5 operation of the switch, a remote controlled signal controlling relay to govern the operation of the signal, and a check locking circuit for the route controlled by the switch controlling means of each switch of the route and arranged to render the remote controlled signal controlling relay ineffective to clear the signal unless each switch of the route agrees as to position with its respective remote controlled switch controlling means.

69. In combination, a railway track switch, a 15 first signal for governing traffic in one direction over the switch, a second signal for governing traffic in the opposite direction over the switch, a first manually operable contact, a second manually operable contact mechanically independent 20 of said first contact, a relay controlled by said first contact for controlling said switch and said first signal, and a second relay controlled by said second contact and electrically interlocked with said first relay for controlling said switch and 25 said second signal.

70. In combination, a stretch of railway track including a track switch, a plurality of signals for governing the movement of traffic over said switch, a plurality of independently operable 30 manual control levers including one for each signal, and means controlled in response to a single operation of any one of said levers provided no other lever has been operated for operating said switch and for selectively clearing the signal 35 corresponding to said lever.

71. In combination, a stretch of railway track including a plurality of track switches, a plurality of signals for governing the movement of traffic over said switches, a plurality of independently operable manual control levers including one for each signal, and means controlled in response to the operation of any one 40 of said levers provided no other lever has been operated for operating each of said switches and 45 for clearing the signal corresponding to said lever.

72. In combination, a stretch of railway track including a two position track switch, means for governing the movement of traffic over a plurality 50 of routes each including said switch comprising a signal at the entering end of each route, a plurality of independently operable manual control levers including one for each route, each having a normal and a reverse position, and 55 means effective when any one of said levers is moved to its reverse position provided the remaining levers are in their normal positions for operating said switch to render available the route corresponding to said lever and for automatically clearing the signal for said route when 60 said route is rendered available.

73. In combination, a stretch of railway track including a two position track switch, means for governing the movement of traffic over a plurality 65 of routes each including said switch comprising a signal at the entering end of each route, a plurality of independently operable manual control levers including one for each route, each having a normal and a reverse position, a 70 relay for each lever, means effective when any lever is moved to its reverse position for energizing the corresponding relay provided none of the remaining relays are energized; means controlled by each relay when energized for operating said switch to render available the route cor-

responding to said lever, and for automatically clearing the signal for said route when said route is rendered available.

74. In combination; a stretch of railway track; a signal at each end of said stretch, each governing movement of traffic into said stretch; a free and unlockable lever for governing each of said signals; a track switch at an intermediate point in said stretch of track; a free and unlockable lever for said track switch; and unitary timing 5 means effective at times to prevent the operation of said track switch in response to its lever, and at other times to prevent a reversal of traffic movement permission by said signals over a particular route, said means being effective for a 10 predetermined time following the restriction of traffic movement over such route.

75. In combination, a circuit, extending between two electroresponsive signal operating mechanisms respectively associated with the opposite ends of a section of railway track over which traffic is to move in either direction and containing a track switch, a current source at each end of the circuit for supplying current to said circuit but normally disconnected therefrom, 20 a central office controlled relay associated with each end of the circuit, means governed by each central office controlled relay when energized to connect the associated current source with said circuit, signals governed by said mechanisms to 25 permit traffic to move through the section in a direction determined by the end at which said circuit is supplied with current, and contacts in said circuit assuming a position in accordance with the position assumed by said track switch. 30

76. In combination, a stretch of railway track, a signal at each end of said stretch each governing movement of traffic into said stretch, a track switch at an intermediate point in said stretch, a route wire extending from one to the other of said signals and including a contact closed only if said switch is in a position to establish a route over said stretch and connected at each end to the same terminal of a source of current, an electroresponsive means associated 40 with each of said signals for controlling such signal, and manually controllable means for each such electroresponsive means for connecting that end of the route wire to the opposite terminal of said source and including the associated electroresponsive means in said route wire. 45

77. In combination, a stretch of railway track, a signal at each end of said stretch each governing movement of traffic into said stretch and each comprising electroresponsive means for governing the aspect displayed by the signal, a track switch at an intermediate point in said stretch, a route wire extending from one to the other of said signals and including a contact closed only if said switch is in a position to establish a 50 route over said stretch and connected at each end to the same terminal of a source of current, and manually controllable means for each such signal for connecting the corresponding end of the route wire to the opposite terminal of said 55 source in series with the electroresponsive means of the signal at that end of the route wire.

78. In combination, a stretch of railway track; two signals, each governing movement of traffic into said stretch; manual control means for each 60 of said signals; a track switch at an intermediate point in said stretch of track; manual control means for said track switch; and a time element means for each of said signals effective, when a train is in approach to that signal, to prevent both 65

the response of said track switch to its manual control means and the response of said other signal to its manual control means for a predetermined time after that signal having a train 5 in approach thereto has been caused to display stop by its manual control means.

79. In combination; a stretch of railway track; a signal at each end of said stretch, each governing movement of traffic into said stretch; manual 10 control means for each of said signals; a track switch at an intermediate point in said stretch of track; manual control means for said track switch; and a time element means for one of said signals effective, when a train is in approach 15 to that signal, to prevent both the response of said track switch to its manual control means and the response of said other signal to its manual control means for a predetermined time after that signal having a train in approach thereto 20 has been caused to display stop by its manual control means.

80. In combination; a stretch of railway track; two signals, each governing movement of traffic into said stretch; a free and unlockable lever for 25 each of said signals; a track switch at an intermediate point in said stretch of track; a free and unlockable lever for said track switch; and a time element means for each of said signals effective, when a train is in approach to a signal, to prevent 30 both the response of said track switch to its lever and the response of said other signal to its lever for a predetermined time after the first signal has been manually caused to display stop.

81. In combination; a stretch of railway track; a signal at each end of said stretch, each governing movement of traffic into said stretch; a free and unlockable lever for each of said signals; a track switch at an intermediate point in said 40 stretch of track; a free and unlockable lever for said track switch; and a time element means for one of said signals effective, when a train is in approach to a signal, to prevent both the response of said track switch to its lever and the 45 response of said other signal to its lever for a predetermined time after the first signal has been manually caused to display stop.

82. In combination, a stretch of railway track, two signals governing the entrance of traffic into 50 said stretch by indicating proceed or stop, a free and unlockable lever for each of said signals, each of said levers so controlling its respective signal that it can be caused to indicate proceed only when traffic conditions are proper in said 55 stretch, and a time measuring means effective under certain traffic conditions when one of said signals is caused to indicate stop after indicating proceed, to measure off a predetermined time before the other signal can be caused to indicate proceed in accordance with traffic conditions.

83. In combination, a stretch of railway track, two signals governing the entrance of traffic into 60 said stretch by indicating proceed or stop, a free and unlockable lever for each of said signals for causing such signal to at times indicate proceed, and a time measuring means effective under certain traffic conditions when one of said signals is caused to indicate stop after indicating proceed to prevent the other signal from indicating proceed for a predetermined time interval.

84. In combination with a detector section of 70 railway track containing a track switch, having an adjacent approach section, a first signal for governing the movement of traffic from said approach section into said detector section, a second

signal for governing the movement of traffic in the opposite direction into said detector section, manual control means for the switch, and for each signal, and time measuring means effective when the approach section is occupied and the first signal has been cleared to prevent the response of the switch to an operation of its manual control means and to also prevent the clearing of the second signal by an operation of its manual control means for a predetermined time 10 after the first signal is manually restored to stop. 5

85. In combination with a stretch of railway track having an adjacent approach section, a first signal for governing the movement of traffic from said approach section into said stretch, a second signal for governing the movement of traffic in the opposite direction into said stretch, a control contact for each of said signals, and a locking relay effective when the first signal has been cleared in response to the closing of its control contact and the approach section is occupied, to prevent the clearing of the second signal in response to the closing of its control contact, for a predetermined time after said first signal has been put to stop. 20

86. In an interlocking system for railroads, a track section having a track relay, a signal governing the movement of traffic over said track section in one direction, a manually controlled relay for controlling said signal, a directional 30 stick relay associated with said track section, a pick-up circuit for said directional stick relay including a front contact of said track relay, a stick circuit for said directional stick relay including a contact closed when the manually controlled relay is deenergized, and traffic controlled means governed by said directional stick relay. 35

87. In a relay interlocking system for railroads, a stretch of railway track comprising a detector section including a track switch, and a second 40 section, each having a track relay, a pair of manually operable control relays including one for each end of the stretch for establishing direction of traffic movement through the stretch, a route locking relay having a pick-up circuit including 45 a front contact of the track relay for the second section and a stick circuit controlled in accordance with the traffic direction established by said control relays, and a control circuit for the switch including manually controlled contacts and controlled by front contacts of the route locking relay and of the detector section track relay. 50

88. In a relay interlocking system for railroads, a track layout comprising a plurality of track sections including a detector section containing a track switch, a track relay for each section, electrically interlocked manually operable control relays for establishing the direction of traffic movement through the stretch, a route locking relay for each section except said detector section each having a pick-up circuit including the front contact of the track relay for the corresponding section and a stick circuit so controlled in accordance with the direction of traffic established by said control relays as to be 65 closed when the corresponding section is occupied by a train moving away from said detector section, and a control circuit for the switch including manually controlled contacts and controlled by front contacts of said route locking relays and of the track relay for the detector section. 70

89. In a relay interlocking system for railroads, a track layout comprising a plurality of track portions capable of interconnection by a 75

- track switch to form different traffic routes, signals for governing the movement of traffic through said layout in either direction, a control relay for each signal, a circuit network arranged as a counterpart of the track layout including a conductor for each track portion, switch indication contacts controlled by the track switch for interconnecting said conductors to form route circuits each of which is a counterpart of a traffic route determined by the switch, a contact at each free end of the network controlled by one of said control relays, manual means for actuating said control relays to selectively energize a particular route circuit at one end or the other, and means responsive to the flow of current in one of said route circuits for clearing the signal governing the corresponding traffic route for the direction corresponding to the direction of current flow in such circuit.
90. In a relay interlocking system for railroads, a track layout comprising a plurality of track portions capable of interconnection by track switches to form different traffic routes, signals for governing the movement of traffic through said layout in either direction, a control relay for each signal, a circuit network arranged as a counterpart of the track layout including a conductor for each track portion, switch indication contacts controlled by the track switches for interconnecting said conductors to form route circuits which are counterparts of the traffic routes determined by the switches, a contact at each free end of the network controlled by one of said control relays, manual means for selectively actuating said control relays to energize a particular route circuit at one end or the other, and means responsive to the flow of current in any route circuit for clearing the signal governing the corresponding traffic route for the direction corresponding to the direction of current flow in said circuit.
91. In a relay interlocking system for railroads, a track layout comprising a plurality of track portions capable of interconnection by track switches to form different traffic routes, signals for governing the movement of traffic through said layout in either direction, a control panel including a representation of the track layout and including a plurality of manually operable keys including one key for each signal of the layout, a plurality of control relays controlled by said keys, each having a contact corresponding to a particular signal of the layout, a circuit network including conductors interconnected by contacts controlled by the track switches to form route circuits each of which is the counterpart of a traffic route through the layout, means for actuating said control relays according as said keys are selectively operated to selectively energize a particular route circuit at one end or the other, and means responsive to the flow of current in any route circuit for clearing the signal governing the corresponding traffic route for the direction corresponding to the direction of current flow in said circuit.
92. In combination with a stretch of railway track having two opposing signals controlled by traffic conditions, including one signal at each end of the stretch for governing the movement of traffic through the stretch, a manually controlled relay for each signal, and a circuit network for controlling said signals comprising a circuit for each signal selectively controlled by the relay for such signal so that but one circuit can be energized at a time, said circuits having portions in common including contacts of one or more traffic control devices which control both signals and at least one of said circuits having a portion including contacts of one or more traffic control devices which control the corresponding signal but not the other signal.
93. In combination with a stretch of railway track including a track switch and having a pair of opposing signals including one at each end of the stretch for governing the movement of traffic through the stretch, a manually controlled relay for each signal, and a circuit network for controlling said signals comprising a circuit for each signal including a contact closed when the relay for such signal is energized, a contact which opens when the relay for the opposing signal is energized, and a source of energy, said circuits having portions in common including a contact closed only when the track switch is in a position to complete a traffic route from one signal to the other, at least one of said circuits also having a portion including a contact closed only when the section is unoccupied.
94. In combination with a stretch of railway track including a track switch and having a pair of opposing signals including one at each end of the stretch for governing the movement of traffic through the stretch, a manually controlled relay for each signal, and a circuit network for controlling said signals comprising a circuit for each signal including a contact closed when the relay for such signal is energized, a contact which opens when the relay for the opposing signal is energized, and a source of energy, said circuits having portions in common including a contact closed only when the track switch is in a position to complete a traffic route from one signal to the other, at least one of said circuits also having a portion including a contact closed only when the section is unoccupied.
95. In combination with a stretch of railway track having two opposing signals including one at each end of the stretch for governing the movement of traffic through the stretch, a pair of manually controlled relays, and interlocked energizing circuits for each of said signals, the circuit for the first signal including a contact of the first relay of the pair closed when the relay is energized, a common portion including a contact closed only when the track switch is in a position to complete a traffic route from one signal to the other, a contact of the second relay closed when the relay is deenergized, and a source of energy, the circuit for the second signal including a contact of the second relay closed when the relay is energized, said common portion, a contact of the first relay closed when the relay is deenergized, and a source of energy.
96. Interlocking control apparatus for a plurality of interconnected railway tracks, comprising a plurality of signals for governing traffic movements over said tracks, a route check circuit network for providing interlocking control of said signals, and a signal control circuit network for checking the route check circuit network.
97. Interlocking control apparatus for a plurality of interconnected railway tracks, comprising a plurality of signals for governing traffic movements over said tracks, a route check circuit network and a signal control circuit network each of which checks the other and provides interlocking control, and means controlled by said network circuits for controlling said signals.
98. In combination, a track switch, signals for

governing traffic over each of the four possible routes over said track switch, four route relays one for each of said signals, means for clearing that one of said signals which has its corresponding route relay picked up only when said track switch is in a proper position and locked for that route, means for manually governing the picking up of said route relay, and means allowing the picking up of only one of said route relays at 10 any one time.

99. In combination; a track switch; signals for governing the traffic over each of the four possible routes over said track switch; four route relays, one for each of said routes; means for 15 clearing one of said signals when its corresponding one of said route relays is picked up only if said track switch is in a position to physically establish that route and is locked; means for 20 manually governing the picking up of each of said route relays; means allowing the picking up of only one of said route relays at any one time; and means for sticking up at least one of said route relays subject to traffic conditions adjacent 25 said track switch.

100. In an interlocking system for railroads, a track layout having a plurality of tracks interconnected by a plurality of track switches to form a plurality of partly interinclusive routes, a plurality of signals for governing traffic through 30 said routes, a route relay for each route, means for controlling said switches by certain of said route relays, signal control means for controlling said signals by certain of said route relays subject to traffic conditions except when specially 35 controlled, and manually operable means for impressing special control on said signal control means for clearing a signal for a route independently of said traffic conditions but dependent upon said route relay for that route.

101. In an interlocking system for railroads, a track layout having a plurality of tracks interconnected by a plurality of track switches to form a plurality of partly interinclusive routes, a plurality of signals for governing traffic through said 40 routes, a route relay for each route, means for controlling said switches by certain of said route relays, signal control means for controlling said signals for any route by the corresponding one of said route relays subject to traffic conditions except when specially controlled, and manually 45 operable means for impressing special control on said signal control means for clearing a signal for a route independently of said traffic conditions but dependent upon said route relay for that route.

102. In an interlocking system for railroads, a track layout having a plurality of tracks interconnected by a plurality of track switches to form a plurality of different routes, a plurality of signals for governing traffic through said track layout, a miniature track diagram corresponding to said track layout, a route button on said track diagram for each of said signals and in corresponding positions, contacts operated by each of said route buttons, a route circuit for each of said routes through said track layout, a route relay included in each of said route circuits, switch operating means controlled by each route relay for operating each of said track switches included in its route to a position proper for establishing such route, signal control means controlled by each of said route relays for clearing the one of said signals governing traffic over such route, 55 manually operable means for each signal for im-

pressing additional control on said signal control means subject to said route relays governing said signal control means, and means requiring said switches for a route to respond to their respective switch operating means before said signal control 5 means for that route can be effective.

103. In an interlocking system, the combination with a track lay-out including a track switch, a plurality of signals for governing traffic in both directions over the two routes establishable by 10 said track switch, a switch machine for operating said track switch, lock-out means for preventing operation of said switch machine, a circuit including a lever operated contact for controlling a relay for in turn controlling said switch machine and permitting control of said relay only if said lock-out means is inactive, an indicating relay for indicating the position of said switch machine and whether it is in correspondence with its control relay, three route circuit portions, and 15 two route circuits for interlocking said signals each including two of said route portions and a contact of said indicating relay.

104. In an interlocking system, the combination with a track lay-out including a track switch, a plurality of signals for governing traffic in both directions over the two routes establishable by 20 said track switch, a switch machine for operating said track switch, lock-out means for preventing operation of said switch machine, a circuit including a lever operated contact for controlling a relay for in turn controlling said switch machine and permitting control of said relay only when said lock-out means is inactive, an indicating relay for indicating the position of said 25 switch machine and whether it is in correspondence with its control relay, three route circuit portions, and a contact operated by said track switch for connecting said circuit portions to establish route circuits each corresponding to 30 the track route then established.

105. In an interlocking system, the combination with a track lay-out including switches and a cross-over to establish a plurality of track routes, contacts associated with said switches and cross-over 35 said contacts having circuit closing positions corresponding to the positions of their track points, wires connecting said contacts to establish route circuits corresponding to track routes established by said switches and cross-over, a 40 signal at each end of each track route, and interlocking means including an established route circuit for allowing clearing of a signal at one end of the corresponding established track route only.

106. In an interlocking system, the combination with a track lay-out including switches and a cross-over to establish a plurality of track routes, contacts associated with said switches and cross-over 45 said contacts having circuit closing positions corresponding to the positions of their track points, wires connecting said contacts to establish route circuits corresponding to track routes established by said switches and cross-over, a signal at each end of each track route, energizing means at each end of each route circuit for 50 energizing such route circuit when established, interlocking means for preventing the energizing means at one end of a route circuit functioning when the energizing means at the other end of said route circuit is effective, and a signal control circuit governed jointly by said energizing means and its associated interlocking means.

107. In an interlocking system, the combination with a track lay-out including a track switch, four signals for governing traffic in both direc- 55

tions over the two routes establishable by said track switch, a switch machine for operating said track switch, lock-out means for preventing operation of said switch machine, a circuit including 5 a lever operated contact for controlling said switch machine and permitting control of said switch machine only when said lock-out means is inactive, three route circuit portions, and two route circuits for interlocking said signals each including two of said circuit portions.

108. In an interlocking system, the combination with a track lay-out including a track switch, a plurality of signals for governing traffic in both directions over the two routes establishable 15 by said track switch, a switch machine for operating said track switch, lock-out means for preventing operation of said switch machine, a circuit including a lever operated contact for controlling said switch machine and permitting control 20 of said switch machine only when said lock-out means is inactive, three route circuit portions, and two route circuits for interlocking said signals each including two of said circuit portions.

109. In an interlocking system, the combination with a track lay-out including a track switch, a plurality of signals for governing traffic in both directions over the two routes establishable by said track switch, a switch machine for operating 30 said track switch, lock-out means for preventing operation of said switch machine, a circuit including a lever operated contact for controlling said switch machine and permitting control 35 of said switch machine only when said lock-out means is inactive, three route circuit portions each corresponding to a track portion isolatable by said track switch, and contacts operated by said track switch for connecting said circuit portions to establish route circuits each corresponding to the track route then established.

110. In combination, a railway track switch, a polarized switch control relay, means controlled by said relay for operating said switch to normal or reverse position according as said relay is energized in a normal or a reverse direction, a polarized indication relay, means for energizing said indication relay in a normal or a reverse direction when said switch assumes its normal or reverse position, a normal indication relay controlled by a normal polar contact of said control relay and by a normal polar contact of said polarized indication relay, a reverse indication relay controlled by a reverse polar contact of said control relay and by a reverse polar contact of said polarized indication relay, a manually controlled relay, two signals for governing the movement of traffic over different routes determined by the position of the switch, a circuit for one 60 of said signals including contacts of the manually controlled relay and of the normal indication relay, and a circuit for the other of said signals including contacts of the manually controlled relay and of the reverse indication relay.

111. In combination, a stretch of railway track including a track switch, a plurality of signals for governing the movement of traffic over different traffic routes determined by the position of the switch, a miniature track diagram of said 70 stretch including means for visually representing each of said traffic routes, a manually operable lever contact adjacent the representation of each signal of the diagram, and electrically interlocked relay means responsive to the closing of any one 75 of said lever contacts when all of the remaining

contacts are open for clearing the corresponding signal and for indicating the corresponding route on said diagram.

112. In an interlocking system for railroads, a stretch of railway track including a track switch, a plurality of signals for governing the movement of traffic over different routes determined by the position of the switch, a track diagram arranged to form a miniature representation of said stretch, a plurality of manually operable lever contacts 10 mounted on said diagram including one for each route located at one end of the representation of the corresponding route, and relay means interlocked non-mechanically and controlled by said lever contacts for selectively clearing said 15 signals.

113. In an interlocking system for railroads, a stretch of railway track including a track switch, a plurality of signals for governing the movement of traffic over different routes determined by the 20 position of the switch, a track diagram arranged to form a miniature representation of said stretch, a plurality of manually operable lever contacts mounted on said diagram including one for each route located at one end of the representation of 25 the corresponding route, a control relay for each lever contact adapted to become energized when such contact is closed, means rendered effective when any of said control relays become energized to cause the control relays associated with 30 conflicting routes to become nonresponsive to the closing of their lever contacts, and other means rendered effective when such control relay becomes energized to clear the corresponding signal.

114. In combination, a detector section of rail-way track including a track switch, an approach track section adjacent said detector section, a signal for governing the movement of traffic over a route extending from said approach section into said detector section, a control relay for said 40 signal, a circuit for clearing said signal including a contact closed when its control relay is energized and the track switch is in a position to establish said route, means for energizing said control relay comprising a manually controllable 45 lever contact, and means for locking said control relay to prevent its release if said lever contact is opened when the approach section is occupied by a train approaching the signal at clear.

115. In combination, a traffic route including a 50 plurality of railway track switches, a signal at each end of the route for governing the movement of traffic over the route, a remotely controlled switch control means for each switch, a remotely controlled signal relay for each signal, a route 55 circuit for each signal controlled by the remotely controlled means for the signal and by the switch control means for each switch of the route, and arranged to be closed only if each switch of the route agrees in position with its control means, 60 a route relay for each signal controlled by the corresponding route circuit, and a control circuit for each signal closed only when its route relay is energized.

116. In an interlocking system for railroads, a 65 track layout including two converging tracks joined by a two-position track switch, a control panel provided with a track diagram comprising a miniature representation of said layout, two lamps for illuminating the tracks of said diagram, 70 one being included in each of the converging tracks adjacent the switch of said diagram, control means associated with said panel for operating the track switch, switch indication means controlled by the track switch, and means controlled 75

jointly by said control means and said switch indication means for lighting one lamp or the other in accordance with the position of the track switch provided the switch and its control means occupy corresponding positions.

117. In an interlocking system for railroads, a track layout comprising a plurality of track sections adapted to be interconnected by track switches to form different traffic routes, a track diagram comprising a miniature representation of the track layout, a plurality of lamps included in the track rails of said diagram including a series for displaying an illuminated representation

of a particular traffic route through said layout, means for operating one or more of said track switches as required to establish said route, means governed by said control means for lighting certain of said lamps and extinguishing others to indicate the portions of said route that are already established, and means governed by the track switches and rendered effective when said switches assume their operated positions to light the remaining lamps of said series to indicate a complete route on said diagram as soon as said route is fully established through said layout.

HOWARD A. THOMPSON.
